UNITED STATES PATENT OFFICE

JAY J. REKAR, OF LOS ANGELES, CALIFORNIA

DESIGN FOR A PORTABLE-STANDARD TRANSFORMER FOR ORIFICIAL APPLICATORS

Application filed March 5, 1932. Serial No. 43,089. Term of patent 14 years.

To all whom it may concern:

Be it known that I, JAY J. REKAR, a citizen of the United States, and resident of the city of Los Angeles, Los Angeles County, State of California, have invented a new, original, and ornamental Design for a Portable-Standard Transformer for Orificial Applicators, of which the following is a specification, reference being had to the accompanying drawing, forming a part hereof.

The figure is a perspective of the transformer.

I claim:

The ornamental design for a portable-standard transformer for orificial applicators, substantially as shown.

JAY J. REKAR.
